5 SHEETS—SHEET 3:

Fig. 3.

This technical drawing illustrates a mechanical assembly, likely a component of a larger machine. The assembly is mounted on a vertical frame 35. It features two parallel vertical columns of components. Each column includes a central rectangular housing with a slot 49. Within these slots are two circular components, possibly bearings or pulleys, supported by springs 48. Long, thin rods 46 extend downwards from these components. The lower ends of these rods are attached to large, serrated gears 53, which mesh with a single, large, serrated gear 54 at the bottom. On the left side of the assembly, two cylindrical components 50 are mounted, each with a handle 51. On the right side, there is a vertical rod 36 with a handle 37, and a horizontal rod 38. A small rectangular component 63 is positioned at the top. The bottom right corner of the drawing contains the number 60.

UNITED STATES PATENT OFFICE.

SOLOMON GERMAN, OF JESSUPS, MARYLAND.

PROCESS FOR HUSKING CORN.

1,194,616.

Specification of Letters Patent. Patented Aug. 15, 1916.

Application filed February 16, 1916. Serial No. 78,565.

To all whom it may concern:

Be it known that I, SOLOMON GERMAN, a citizen of the United States, residing at Jessups station, in the county of Howard and State of Maryland, have invented certain new and useful Improvements in Processes for Husking Corn, of which the following is a specification.

This invention relates to a novel and improved method of removing the husks from ears of corn, and its object is to facilitate the husking operation, the same being accomplished by removing the husks in a manner to be hereinafter described.

In order that the invention may be better understood, I have shown in the accompanying drawings an apparatus whereby the process may be effectually carried out.

In the drawings—Figure 1 is a plan view 20 of the machine with parts broken away: Fig. 2 is an end view, partly in section: Fig. 3 is an end view of the husking mechanism: Fig. 4 is a vertical cross-section of the husking mechanism: Fig. 5 is an elevation, partly in section, of a modified form 25 of husking mechanism: Fig. 6 is a side elevation of a husk severing device, and Fig. 7 is a front elevation of said device.

Referring specifically to the drawings, 10 Fig. 10 denotes a wheeled truck on which the mechanism is mounted, so that it may be conveniently hauled from place to place. Of course, the machine may be built stationary, but it is, preferably, made portable.

The truck 10 carries uprights or standards 11 rising to a suitable height and supporting at the top a table or platform 12, and on the latter is mounted another table 13, the same being supported a suitable distance 20 above the table 13 by standards 14. The table 13 is designed to receive the corn stalks, one end of the same being adjacent to the discharge end of an endless conveyer 14'. From the receiving end of the table 45 13, the same slopes down toward the opposite end where the operator stands, and the stalks therefore roll down to this end of the table, where they are taken up by the operator and presented to a rotary cutter 50 in the form of a circular saw 15 to cut the ears from the stalks. The saw is on a shaft 16 which is belted or otherwise connected, as indicated at 17, to a countershaft 18, the latter, in turn, being belted or otherwise 55 suitably connected, as indicated at 19, to a motor 20 which may be an internal com-

bustion engine mounted on the truck 10. Any other suitable driving means may be provided.

The saw 15 is designed to cut the ears 60 from the stalks at a point where the husks are joined to the cob, so as to leave the husks entirely free and thus facilitate the stripping operation. As the growth of the husks is sometimes such that they are not severed 65 by the saw, there is provided an auxiliary cutter illustrated in detail in Figs. 6 and 7. As here shown, the auxiliary cutter is a flat blade 21 which tapers toward one end and is formed at this end with a centering 70 point 22. This cutter is fixed on the end of the shaft 16 adjacent to the saw 15, and on said shaft is also fixed a guard 23 for the cutter, said guard being a hood which incloses the cutter, the latter being located 75 centrally within the hood, and the hood having a sight opening 24 in its side so that the operation of the cutter may be observed. The hood flares outward and is open at its outer end for the insertion of 80 the ear.

In operation, the ear is manually inserted into the hood 23 from the open end thereof, with its butt end presented to the auxiliary cutter, and it is pushed forward into the 85 rotating cutter, the point 22 entering the butt and being followed by the blade 21. As the cutter rotates, a hole is cut in the butt end of the cob, the cut being from the center outward. The ear is manually advanced 90 until enough of the butt end of the cob has been removed to sever the husks and leave the same disconnected from the cob.

From the above described operation, it will be seen that the butt end of the cob will 95 be cut gradually from its center outwardly, and thus removes the cob from beneath the husk connections, thereby leaving the husks lying loosely on the ears and without the stubs forming their connections with the 100 cob. This leaves the severed ends of the husks free from stalky protuberances and facilitates their ready removal from the ears.

Adjacent to the saw 15 and the auxiliary cutter 21 is an inclined chute 25 leading to 105 the husking mechanism which will now be described: In a housing 26 suitably supported in fixed position on the truck 10, is mounted a rotary brush consisting of a hollow cylinder 27 on the inside of which are 110 fixed bristles 28, the same being arranged spirally. The brush cylinder 27 is supported

in a bearing 29 suitably mounted in the housing 26 and has at the top a retaining ring 30 engaging the bearing, whereby the cylinder is prevented from slipping down 5 in the latter.

On the outside of the brush cylinder 27 is a circular rack 31 which is in mesh with a gear 33, the latter in turn being in mesh with a gear 34 on a shaft 35 supported in 10 bearings 36 carried by the housing 26, the latter also carrying a stud 37 in which the gear 33 turns. The shaft 35 is connected by a universal joint 38 to a shaft 39 and the latter is connected by a universal joint 15 40 to a shaft 41, supported in bearings 42 mounted on the table 12. The shaft 41 is driven from the countershaft 18 through a sprocket-and-chain, or other suitable gearing 43. It will thus be seen that the brush 20 cylinder 27 is driven from the countershaft 18. The shaft 41 has a sliding or other clutch 44 so that the brush cylinder may be thrown into and out of gear at the will of the operator.

25 A means is provided for feeding the ears through the brush cylinder 27, the same comprising two pairs of grooved feed rollers 45 located in advance of the entrance end of the cylinder. The members of the 30 respective pairs of feed rollers are yieldingly pressed toward each other by mounting the shafts 46 thereof in bearing blocks 47 which are slidably mounted in slotted supports 48 and backed by springs 49. The housing 26 35 carries the supports 48 and also carries nuts 50 which are provided with screws 51 for adjusting the tension of the springs. The sides of the housing 26 carrying the supports 48 have openings in which the latter 40 are mounted. The feed rollers yield to allow ears of different diameters to pass therebetween, and they are so spaced that the ears are gripped when placed therebetween, whereby they are fed forward.

45 The following drive gear for the feed rollers 45 is provided: Below the brush cylinder 27, the housing 26, on the outside thereof, carries two shafts 52 provided each with a sprocket wheel 53 and a gear 54. The 50 sprocket wheels 53 are connected by chains 55 to sprocket wheels 56 on one end of the shafts of the upper pair of rollers 45. On the shafts of the lower pair of rollers 45 are sprocket wheels 57 which are connected 55 by chains 58 to sprocket wheels 59 mounted on stub shafts 59' secured to the opposite side of the housing 26 from that on which the shafts 52 are located. Sprocket chains 59" are trained over sprocket wheels fixed 60 to and corresponding with the wheels 59 as shown dotted in Fig. 4. The two gears 54 are in mesh with each other, and in mesh with one of said gears is a drive pinion 60 fast on a shaft 61 suitably supported on the 65 outside of the housing 26. The shaft 61 is

belted or otherwise operatively connected to the counter shaft 18, as indicated at 62. Thus it will be seen that the two sets of feed rollers 45 are driven from the countershaft 18, the motion of the latter being transmitted 70 to the shaft 61 by the belt 62. The motion of the shaft 61 is transmitted by the pinion 60 and the gears 54 to the shafts 52, and the upper set of rollers is driven from the shafts 52 by the chains 55, whereas the lower 75 set is driven from the shafts 46 by the chains 59", and chains 58.

The chute 25 leads to the upper or entrance end of the housing 26, and here are spring-hinged wings 63 which extend 80 convergingly downward and direct the ears to the upper set of feed rollers 45.

The housing 26 opens at the bottom into a suction box 64 connected by a conduit 65 to the inlet of a rotary fan 66 driven by a belt 67 from the countershaft 18. The suction box has a bottom opening 68 over an inclined chute 69 down which the husked ears slide to a suitable receptacle (not shown). The chute has a perforated portion 70 below which is mounted a hopper 71. Any grains of corn which may drop off the ears pass through the perforations into the hopper, a bag or other suitable receptacle being hung thereon to receive the 95 grains.

The conveyer 14' is driven from the countershaft 18, the latter being geared to a shaft 72 as indicated at 73, and the shaft 72 is connected by a sprocket-and-chain 100 gearing 74 to the top shaft of the conveyer.

In operation, the ears severed from the stalks as already described, are thrown into the chute 25 which conveys them to the husking mechanism. The ears drop into the hopper formed by the wings 63 which rights them and presents them endwise to the top feed rollers 45, one after the other. The ear then passes down to the lower feed rollers 45 and is grasped by the latter and pushed down through the brush cylinder 27, where the husks are removed by the action of the bristles 28. The brush cylinder revolves, but the ear does not turn, in view of which the husks are quickly brushed off. 110 If the husks are dry, the brush cylinder may be stopped, and the ears just pushed through the same, which is sufficient to remove the husks. It is only when the husks are more or less green and cling close to 115 the cob that the rotary motion of the brush is necessary to effect the removal of the husks. When the husks are dry they will be readily stripped off with the brush cylinder stationary, and this also reduces to a 120 minimum the shelling of the corn. The husked ears drop on the chute 69 to be disposed of as already described. The husks drop into the box 64 and are sucked by the fan 66 into the conduit 65 which latter car- 130

ries the husks to the place of disposal. Preferably, the husks and the stalks will be tied into bundles, a suitable bundling mechanism being provided for this purpose.

5 Fig. 5 illustrates a modified form of husking brushes, the same comprising two cylinder brushes 75 mounted face to face in spaced relation so that the ears may pass therebetween. Each brush is mounted on a 10 shaft 76 which is slidably mounted in a hollow shaft 77, the latter carrying a radial pin 78 which seats in a longitudinal slot 79 in the former to provide a driving connection between the two shafts and also to 15 permit the shaft 76 to slide. In the shaft 77 is mounted a spring 80 which abuts at one end against a plug 81 closing the outer end thereof, and at its other end against the end of the shaft 76. Both brushes 75 are 20 mounted in this manner and they are therefore free to yield or spread to permit the passage therebetween of different sized ears. The springs yieldingly hold the brushes pressed against the ears. The brushes are 25 rotatable, they being driven by the drive mechanism of the feed rollers 45. Thus, one

of the shafts 77 is connected by a sprocket-and-chain gearing 82 to the shaft of one of the lower feed rollers, whereas the other brush shaft 77 is connected by a sprocket-and-chain gearing 83 to one of the shafts 52. It will be noted that with the brushes 75, the lower feed rollers 45 are operatively connected to the upper feed rollers by a sprocket-and-chain drive 84.

30

35

I claim;

1. The method of removing husks from ears of corn, consisting of cutting the butt end of the cob from its center gradually outwardly to remove said butt end of the 40 cob from beneath the husk connections.

2. The method of removing husks from ears of corn, consisting of cutting the butt end of the cob from its center outwardly to its connection with the husks, and finally 45 removing the husks from the ears.

In testimony whereof I affix my signature in presence of two witnesses.

SOLOMON GERMAN.
